No. 722,906.

PATENTED MAR. 17, 1903.

L. V. ROOD.

FILTER.

APPLICATION FILED NOV. 7, 1902.

NO MODEL.

UNITED STATES PATENT OFFICE.

LLOYD VINCENT ROOD, OF MARIETTA, OHIO.

FILTER.

SPECIFICATION forming part of Letters Patent No. 722,906, dated March 17, 1903.

Application filed November 7, 1902. Serial No. 130,451. (No model.)

To all whom it may concern:

Be it known that I, LLOYD VINCENT ROOD, a citizen of the United States, residing at Marietta, in the county of Washington and State of Ohio, have invented a new and useful Filter, of which the following is a specification.

This invention relates to that class of pressure-filters which are usually attached for operation to a hydrant; and it has for its object to provide a device of this class which shall be simple, inexpensive, and efficient and in the construction of which shall be embodied a cleaning device whereby the surface of the filtering member may be cleaned whenever desired and freed from the mud and impurities deposited thereon, such cleaning operation performed automatically by the action of water permitted to flow through the filter-casing.

My invention consists in the improved construction, arrangement, and combination of parts, which will be hereinafter fully described, and particularly pointed out in the claims.

In the accompanying drawings, Figure 1 is a vertical sectional view of a self-cleaning filter constructed in accordance with the principles of my invention. Fig. 2 is a horizontal sectional view taken on the line 2-2 in Fig. 1.

Corresponding parts in both figures are indicated by similar numerals of reference.

The casing of my improved filter consists of a cylindrical vessel 1, provided near its upper edge with an exterior annular flange 2. 3 is the cover, which is provided with an annular downward-extending rim or flange 4, engaging the upper end of the vessel or casing 1, between the upper edge of which and said cover a packing-ring 5 is interposed to effect a tight joint. The cover is normally held in position by means of a yoke 6, spanning the cover and terminating in inturned arms which engage under the flange 2 of the casing. A set-screw 8 in the yoke presses downward against the cover to secure the latter in position.

The bottom of the casing 1 has a valved outlet-pipe 9, which is preferably centrally attached to the under side of the bottom. Said bottom has on its upper side a concentric annular flange 10, forming a seat for the

filtering member 11, which is illustrated as consisting of an inverted cylindrical cup of any suitable porous material. A washer 12 is interposed between the lower edge of the filtering member and the bottom of the casing. The upper end of the filtering member is seated in an annularly-flanged disk 13, having a centrally-disposed upwardly-extending spindle 14, the upper end of which is reduced and seated in a recess or pocket 15, formed for its reception in the under side of the cover. It is not essential that this recess or pocket should be extended so as to form a protuberance upon the upper side of the cover, as shown in Fig. 1 of the drawings hereto attached; but this construction is preferred, inasmuch as it admits of a corresponding lengthening of the spindle 14, whereby the parts of the device may be more conveniently assembled. The casing 1 is provided at its lower end with a valved discharge-pipe 16.

The upper end of the casing 1 is provided with a tangentially-disposed inlet 17, directly below the mouth, or opening of which a segmental ledge or flange 18 is formed upon the inner side of the casing, said ledge being horizontally disposed, as clearly seen in Fig. 1.

19 designates a disk having a centrally-disposed hub 20, whereby it is journaled upon the stem or spindle 14 of the device forming the seat for the upper end of the filter member. Said disk is provided with an annular flange, which is disposed approximately in alignment with the inner edge of the ledge 18 and the upper edge of which engages an annular groove 22 in the under side of the cover for the purpose of forming an approximately water-tight joint. The flange 21 is provided with a plurality of radiating leaves or paddles 23. Brushes 24, which are preferably constructed of some suitable non-corrodible metal, are attached to the under side of the disk 19, said brushes being preferably provided with screw-threaded stems or shanks that extend through the said disk and are secured to the latter by means of nuts 25. The brushes are made of a length to extend nearly to the bottom of the casing, and their bristles normally engage the surface of the filtering member, as will be clearly seen in Fig. 1 of the drawings.

From the foregoing description, taken in connection with the drawings hereto annexed, the operation and advantages of the invention will be readily understood. While the filter is in use as such the valve of the pipe 16 is kept closed, and the water entering through the inlet 17 will fill the casing and pass through the body of the filtering member to the outlet 9. When after a period of use the filtering capacity of the device is reduced, owing to the deposits upon the surface of the filtering member, it is only necessary to open the valve 16, which permits of the free passage of water from the filter. Water will thus enter at the inlet 17 with sufficient force to rapidly rotate the disk 19, carrying the brushes 24, which will speedily remove the deposits from the surface of the filter, all impurities being carried off through the outlet 16. The action of the device will be readily understood, the disk 19 with its flange 21 and paddles 23 constituting an ordinary water-wheel and the ledge or flange 18 being sufficiently extended to enable the paddles to receive the full force of the impact of the water.

I desire it to be understood that while I have herein described the preferred construction of my invention I do not necessarily limit myself with regard to the details of the same, but reserve the right to any changes, alterations, and modifications which may be resorted to without departing from the spirit and scope of my invention or sacrificing the utility of the same.

Having thus fully described my invention, I claim—

1. In a device of the class described, a casing having a tangential inlet and suitable outlets, a filtering member within said casing, a cover for the latter having an annular groove in its under side, a flanged disk forming a seat for the upper end of the filtering member and having an upward-extending spindle, a flanged paddle-disk mounted upon said spindle, the flange thereof engaging the annular groove in the under side of the cover, and brush members carried by said paddle-disk.

2. In a device of the class described, a casing having a tangential inlet and suitable outlets, a segmental ledge within said casing ad-

jacent to the mouth of the inlet, a filtering member within said casing, a seat member for the latter having a spindle, and a paddle-wheel mounted upon said spindle and carrying brush members engaging the filtering member. 55

3. In a device of the class described, a casing having a tangential inlet and suitable outlets, a segmental ledge within said casing adjacent to the mouth of the outlet, a filtering member within said casing, a cover for the casing having a recess in its under side, a seat member for the filter having a spindle engaging the recess in the under side of the casing, a paddle-wheel mounted upon said spindle and brushes carried by said paddle and engaging the surface of the filtering member. 60 65

4. In a device of the class described, a casing having a tangential inlet and suitable outlets and provided with an exterior annular flange, a cover for said casing having a recess in its under side, a filtering member within the casing, a flanged disk forming a seat for said filtering member and having an upward-extending spindle engaging the recess in the under side of the cover, and a yoke having inturned arms engaging under the annular flange of the casing and provided with a set-screw bearing against the upper side of the cover to bind the parts together. 70 75

5. In a device of the class described, a casing having a tangential inlet and suitable outlets, a filtering member within said casing, a segmental ledge within the latter adjacent to the mouth of the inlet, a cover having a recess in its under side, a flanged disk forming a seat for the filtering member and having an upward-extending spindle, a flanged paddle-disk upon the latter engaging an annular groove in the under side of the cover and brush members carried by said paddle-disk and engaging the surface of the filtering member. 80 85 90

In testimony that I claim the foregoing as my own I have hereto affixed my signature in the presence of two witnesses.

LLOYD VINCENT ROOD.
